(57) **CLAIM**

The ornamental design for a portable nebulizer, as shown and described.

DESCRIPTION

FIG. 1 is a perspective view of a nebulizer with cap;

FIG. 2 is a left side view thereof;

FIG. 3 is a front view thereof;

FIG. 4 is a rear view thereof;

FIG. 5 is a right side view thereof;

FIG. 6 is a top view thereof;

FIG. 7 is a bottom view thereof;

FIG. 8 is a perspective view of the nebulizer with cap off;

FIG. 9 is a left side view of the nebulizer with cap off;

FIG. 10 is a front view of the nebulizer with cap off;

FIG. 11 is a rear view of the nebulizer with cap off;

FIG. 12 is a right side view of the nebulizer with cap off; and,

FIG. 13 is a top view of the nebulizer with cap off.
The broken line showing of portions of the article is included for the purposes of illustrating structural environment and forms no part of the claimed design.
